UNITED STATES PATENT OFFICE

THOMAS H. McFARLAND AND ROBERT D. LEWIS, OF CARNEGIE, PENNSYLVANIA.

INSULATED RAIL-JOINT.

1,148,179.

Specification of Letters Patent. Patented July 27, 1915.

Application filed February 18, 1915. Serial No. 9,089.

To all whom it may concern:

Be it known that we, THOMAS H. McFARLAND, a citizen of the United States, and a resident of Carnegie, in the county of Alle-

gheny and State of Pennsylvania, and ROBERT D. LEWIS, a citizen of the United States, and a resident of Carnegie, Allegheny county, Pennsylvania, have invented a new and useful Improvement in Insulated Rail-Joints; and we do hereby declare the following to be a full, clear, and exact description thereof.

Our invention relates to an improvement in insulated rail joints.

In the insulated rail joints or splice bars now in use, it is customary to insulate the rails from the splice bars in different ways, such as by means of fiber insulation on the inside and underneath such bars, while the bolts for holding the bars to the rails are insulated from such bars by means of bushings and washers. These joints cause considerable trouble to signal maintenance by the bushings cutting out on the bolts and by the insulation cutting out between the tops of the bars and rails and under the bars and rails, while such bolts are generally specially made and such joints also require the attention of experienced signalmen while being installed or repaired. In other forms these joints have the splice bars insulated from the rails by means of wooden fillers inside and outside of the rail, and by a metal base plate underneath the rail provided with a fiber insulation and washers, while the bolts and washers are also specially made, and such wooden fillers very often become weakened under strain of the engines and rolling stock and cause broken rails.

Our invention, therefore, has for its object to overcome these objections and to provide a simple and efficient joint of such character, which can be easily and cheaply manufactured, can be easily and conveniently installed, repaired or renewed, will do away with a number of parts ordinarily employed on these joints that require attention, adjustment and renewal, and will enable such joint to be maintained more cheaply both as to labor and material than the usual joints of this class.

To these ends our invention consists, generally stated, in the novel arrangement, con-

struction and combination of parts, as hereinafter more specifically set forth and described and particularly pointed out in the claims.

To enable others skilled in the art to which our invention appertains to construct and use our improved insulated rail joint, we will describe the same more fully referring to the accompanying drawing, in which:

Figure 1 is a side elevation of our improved insulated rail joint, partly in section; Fig. 2 is a plan view of the same, partly in section; Fig. 3 is an enlarged sectional view on the line 3—3 Fig. 1; Fig. 4 is an enlarged sectional view on the line 4—4 Fig. 3; Fig. 5 is a sectional view showing another form of our invention; Fig. 6 is a side elevation of another form of angle bars containing the invention; and Fig. 7 is a cross section of the same on line 7—7 Fig. 6.

Like symbols of reference herein indicate like parts in each of the figures of the drawing.

As illustrated in the drawing, our improved insulated rail-joint is shown at A and is formed by the fish-plates or angle bars 1 and 1', which are placed at the usual positions with respect to and on each side of the adjacent ends of the two abutting rails α , and are held in position by means of the usual screw bolts b passing through said bars and rails. These angle bars 1 and 1' are on each side of the rail, with the bar 1 on one side of the joint α' and bar 1' on the other side. At the under ends of each of the angle-bars and adjacent to such joint α' , which is formed by the end faces of the abutting rails α , are the insulated projections 2 and 3, which extend out at right angles from each of the bars, so that such projections on one side of the rails α lie against one another, and one of the said projections, such as 2, is provided with upper and lower and outer end flanges 4 and 5 respectively for overlapping or fitting over and around the other projection 3. The projection 3 has a piece of insulation 6, such as fiber or other suitable material, around the same, which is provided with the flanges 6' thereon for fitting between the flanges 4 and the flanges 6 thereon against the flange

5. Bolts 7 pass through the projections 2 and 3 for holding the same together and in place, and such bolts have a bushing of insulation 8 around the same such as fiber or other suitable material, while between the heads of such bolts and the projections a piece of insulation 7', such as fiber or other suitable material is placed. Our improved insulated rail joint A has the parts assembled in position, as shown by placing the rails *a* on the ties (not shown) in the usual manner, with the angle-bars 1 and 1' bolted thereto by the bolts *b* and the projections 2 and 3 bolted to each other by the bolts 7.

15 Before such parts are thus assembled the end posts *c* are placed between the ends of the abutting rails *a*, which posts are formed of fiber or other suitable insulating material, and are preferably of the same shape 20 and size of such rails in cross-section, so that the heads of the same conforming to the head of the rail will act to support such posts by resting on the projections 2 and 3.

It will be obvious that the form of joint 25 can be applied to old rails in tracks, and in the laying of new rails the posts forming the joint can be fitted together as quickly and as conveniently as the ordinary angle or splice bars now in use, as there are no 30 bushings, washers, plates and other parts to assemble as in ordinary forms of these insulated joints, which thereby renders the joint compact and ready for use at all times, while there will also be a saving on the 35 wear on the end posts or insulation between the rail ends, so that the bolts in angle bars can be kept tight in the rails, which will compel pressure against the flat ends or projections on angle bars when the rails 40 creep or expand, thereby keeping the pressure from such end posts and thus overcoming the frequent renewals of such posts.

It will thus be seen that in the use of our improved insulated rail joint, the insulation 45 on the angle bar or joint projections will overcome any wearing out of the insulation usually employed under the rails and along the angle bars caused by the moisture from the ground, and water, etc., from the trains, 50 and by the vibration of the rails cutting out these insulations, while the expansion and contraction of the parts cutting out the end posts will also be overcome by the form of joint employed. The insulated parts are 55 thus supported above the ties and road bed in a dry position, thereby insuring longer wear of the joint. The construction thus requires much less labor and fiber for assembling and renewals than the ordinary 60 joints, while the employment of skilled labor in maintaining the joint is overcome, as the bolts for holding the angle-bars to the rails and the shape of such bars along the rails are of the same form and shape as those generally in use. The construction will also be

held firmly in place and will lessen the liability of the rails at such joint of moving up and down by the traffic in causing the "whipping" of the joint as in most cases, and without the use of base-plates or other such devices.

As has been found in practice, the projections 2 and 3 may be shortened as shown in the other figures of the drawing, such as is shown in Fig. 5, and if desired the bolts 7 can be placed out of line with each other, as shown in said figure. As shown in Figs. 6 and 7 the bar 1 may be provided with an extension 9 on its angular projection 2 for fitting over the flange 1'' on the bar 1', and between such extension and flange a piece of insulation 10, which is formed of fiber or other suitable material, while in such case one of the bolts 7 need only be used for the 80 projections 2 and 3 and a bolt 7'' used for 85 securing the extension to the flange. The projections 2 and 3 can also be provided with the inclined upper and lower faces 12, as shown in Figs. 6 and 7, and the bolt 7'' can be insulated from the extension 9 by 90 the bushing 11 of fiber or other suitable material around such bolt, while the nut on said bolt is insulated from such extension by the washer 13 of fiber or other suitable material.

Various other modifications and changes in the design and construction of the parts of our improved insulated rail-joint may be resorted to without departing from the spirit of the invention or sacrificing any of 100 its advantages.

What we claim as our invention and desire to secure by Letters Patent is:

1. In an insulating rail joint, the combination with a pair of rails disposed in end-wise abutting relation, of a bar secured to one of said rails, a second bar secured to the other rail, said bars having laterally-extending projections formed so as to interlock against endwise movement, supplementary 105 means for connecting said projections together, and insulation between the opposed faces of said projections.

2. In an insulating rail joint, the combination with a pair of rails disposed in end-wise abutting relation, of a bar secured to one of said rails and terminating adjacent the end of such rail, a second bar secured to the other rail and terminating adjacent the end thereof, said bars having laterally-extending projections formed so as to interlock against endwise movement, supplementary 110 means for connecting said projections together, and insulation between the opposed faces of said rails and between the 115 opposed faces of said projections.

3. An insulated rail-joint having angle-bars on each side of the joint, secured to the rails, each of said bars provided with an angular portion extending out from the same 120

adjacent to the ends of the rails forming said joint, one of said portions having flanges for overlapping the other and said portions being insulated from each other.

- 5 4. An insulated rail-joint having angle-bars on each side of the joint, secured to the rails, each of said bars provided with an angular portion extending out from the same adjacent to the ends of the rails forming said joint, one of said portions having flanges for overlapping the other, and said inclosed portion being provided with an insulation around the same.
- 10 5. A connecting device for railway rails comprising angle bars on each side of the rails and secured thereto, each of said bars

being provided with angular portions extending out from the same adjacent the rail ends forming the joint and insulated from each other, an extension on the projection 20 of one of said bars adapted to engage over the other bar and insulated therefrom, and a bolt for securing said extension to the bar.

In testimony whereof, we the said THOMAS H. McFARLAND and ROBERT D. LEWIS, have 25 hereunto set our hands.

THOMAS H. McFARLAND.
ROBERT D. LEWIS.
